UNITED STATES PATENT OFFICE.

ADOLPH LANGNER, OF CHICAGO, ILLINOIS, ASSIGNOR TO EUGENE DIETZGEN COMPANY, OF CHICAGO, ILLINOIS, A CORPORATION OF DELAWARE.

DEVELOPING APPARATUS.

Application filed March 17, 1928. Serial No. 282,487.

This invention relates to developing apparatus for developing light sensitive material such as paper by the action of chemically active gases such for instance as ammonia gas.

One of the objects of my invention is to provide a semi-automatic type of device adapted to develop a plurality of separate sheets or rolls of paper in separate containers and in a manner such as to preclude the escape of the developing gas to the atmosphere either before, during, or after the developing operation.

Yet another object of my invention resides in providing a developing device having a rotatable turret carrying a plurality of developing tubes or towers in which the separate sheets or rolls of light sensitive material may be inserted together with means for automatically rotating the turret and for bringing the towers or tubes either successively or simultaneously over one or more sources of developing medium such for instance as developing liquid adapted to generate gas or alternatively, the gas itself. An ancillary feature of this aspect of my invention resides in the additional provision of means for supplying each tower or tube with water vapor to accelerate the developing action.

Still another object of my invention resides in the details of construction of the rotatable turret and the tubes or towers carried thereby whereby the turret may be rotated intermittently in a step by step manner, and whereby the light sensitive material may be inserted into the towers from a particular station and whereby the towers are moved directly over pans or containers of liquid ammonia and in a manner such as to preclude escape of ammonia gas to the atmosphere while permitting it to pass into the tower to develop the light sensitive material; whereby the turret carrying the towers is automatically moved step by step or alternatively, may be released to be manually turnable in a continuous manner; whereby the turret is provided with rubber or other suitable gaskets or packing means for preventing the escape of the developing gas; whereby the pans containing the liquid ammonia are mounted in depending relation beneath the rotatable turret; whereby means consisting of a container for water and a heating means therefor is mounted suitably beneath the rotating turret so as to be registerable with the up-

standing towers on the turret; whereby the turret is automatically brought to rest after a complete cycle of movement during which the development of all of the separate sheets or pieces of light sensitive material in the various tubes or towers is accomplished.

Still another object of my invention resides in the details of construction of the support not only for the pans or containers carrying the liquid ammonia and water but also the support for the rotatable turret adapted to move thereover.

These and other objects of my invention will be apparent from a perusal of the following specification when taken in connection with the accompanying drawings wherein:

Figure 1 is a plan view of my device with portions broken away to show the tanks;

Figure 2 is a section on line 2—2 of Figure 1;

Figure 3 is a bottom plan view of my device; and

Figure 4 is a detail view of the switch mechanism and stops.

In general, my improved type of developing apparatus comprises a rotatable turret carrying on its upper surfaces a plurality of up-standing towers or hollow tubes adapted to receive and hold therein separate sheets or rolls of paper to be developed. Means is provided for rotating this turret in a step by step fashion and also in a manner to permit it to be freely rotated by hand if desired. In addition, there is mounted beneath the turret a plurality of containers adapted to hold liquid ammonia for generating developing gas which may pass upwardly through the turret into the hollow tubes when the tubes are brought over the pans. The machine is also provided with means for preventing the escape of the developing gas into the atmosphere while permitting it to pass upwardly into the tubes from the liquid ammonia in the pan and this means is constructed and arranged to permit the free rotation of the turret. The invention also comprehends the utilization of one or more of the pans for containing water and provided with heating means for generating water vapor or steam which likewise is arranged so as to pass into the developing towers or tubes to accelerate the developing action. The pans for the ammonia and the water are arranged arcuately beneath the rotatable turret and are grouped on either side of a feeding station which is

constructed so that the paper to be developed may be inserted from beneath the turret upwardly into the tubes and is then held therein by means of open-work doors which not only hold the paper in the tubes but permit the developed gas to pass upwardly therethrough to develop the light sensitive material. During the rotation of the turret, each tube is positioned either over a pan containing the developing liquid or over a water bath and during the continued rotation of the turret, the tubes pass successively over the feeding station so that fresh paper may be inserted into the hollow tubes or the developed paper may be withdrawn therefrom. The invention also embraces certain minor details such as an automatic means controlled by the rotation of the turret for stopping the motor drive therefor when all of the tubes have been subjected to proper developing action, also a means for locking the table in desired position and also a means for either rotating it intermittently or permitting it to be rotated freely.

Referring now to the drawings in detail, the embodiment herein disclosed is a construction which I have selected merely for the purposes of exemplification and not in any restricted sense. This machine comprises the upstanding legs 2, the upper portions of which carry three radially and inwardly extending bars or arms 4, 6, and 8, the junction of which carry a casting 10 which in turn is of such construction that it provides at top and bottom two bearings 12 and 14 adapted to receive a shaft 16 which in turn carries a spider 18 at its upper end, consisting of a number of radially extending arms. The three supporting legs 2 and the arms 4, 6, and 8 are arranged to support the containers or pans for the developing liquid and the water. To this end the arms and legs carry concentrically disposed inner and outer rings 20 and 22 which form complete circles about the axis formed by the shaft 16. These rings are spaced apart at the legs so as to form circular peripheral supports for arcuately shaped pans 24. These pans are of sufficient length to extend from a point 26 (see Figure 1) about the periphery of the circle to a point 28. I prefer to have a number of pans for the purposes hereinafter set forth, although separate pans may be used if desired. These pans are preferably of sheet metal of such nature as to avoid corrosion by liquid ammonia and are preferably provided with sheet metal tops 30 which close the tops of the pans except for a plurality of holes 32 formed through the tops at spaced apart distances of predetermined length. In addition, the upper surfaces of these sheet metal tops are provided with rubber or felt gaskets 34 which overlie the peripheral edges of the containers as shown clearly in Figure 2. The purpose of these felt gaskets is to provide sealing

surfaces to cooperate with the rotatable turret lying above the containers so as to prevent the escape of the developing gases while permitting the free rotation of the turret in the manner hereinafter specified. Certain of the pans 24 are adapted to hold liquid ammonia or other suitable developing liquid adapted to generate or evolve a developing gas such as ammonia gas and these pans may be filled by suitable filling tubes 36 which pass through the walls of the pan and are arranged so that the filling nozzles 38 extend outwardly laterally of the device. In addition, certain of the other pans are provided with relatively short partitions to form water holding chambers 40 and these chambers are each provided with a suitable type of heater 42 for heating the water in the pan so as to generate water vapor or steam. I prefer to provide an electric heater for this purpose and this heater is provided with any type of electrical connection 44 to the outside portion of the developing apparatus.

As herein shown, I provide two series or sets of pans for holding liquid ammonia and water vapor. The two pans for holding the water vapor are designated as 40 and 46 and it will be noticed that the first water pan 40 is placed immediately after the first ammonia pan 30 and that the last water pan 46 is placed after the second of the ammonia pans and is arranged immediately before the discharging and feeding station.

In order to permit the insertion of sensitized paper into the developing tubes and to withdraw it therefrom after being developed, at one sector, or the under structure of my device, I eliminate the pans and leave that arcuate portion of the periphery of the base open. This is shown at the left in Figure 2 of the drawings. It will be seen that when it is desired to insert or withdraw the material from a tube, it is done from beneath the table or turret. The arms 18 carried by the upper end of the shaft 16 form a support for a table or turret 50. This turret is provided at desired intervals with a number of upstanding towers or chambers 52 arranged in spaced relation about the periphery of the table. In the present instance, there are 12 of such towers. The tops of these towers are closed and the bottoms are open. The bottoms are preferably closed by means of a door 54 hinged as at 56 to the table and the door 54 is of open work construction, preferably wire mesh or screen, and is round so as to snugly fit the bottom of the open tower. The under side of the table opposite the hinge 56 is provided with a spring catch 58 adapted to hold the door 54 in closed position. Each door, when released, will drop by gravity so that a sheet or roll of light sensitive material may be inserted upwardly into the tube after which the door is snapped into closing position so that the door will hold the sheet

of paper or developing material 60 in upright position while at the same time permitting the developing gas to pass upwardly therethrough to develop the paper. It will be noted that the feeding and discharging station is of sufficient arcuate length to provide room for inserting the material into four of the doors, either simultaneously or successively. It will also be observed that the complete circular extent of the turret and the machine is divided into thirds. The first third, or four of the tubes, comprises the feeding and discharging station; the second third is the first developing station and consists of a water container with a heating means located at the head of the series; and three, developing stations comprising the three spaced holes above the first pan containing the liquid ammonia and forming openings over which three hollow tubes are positioned. The second developing station also comprises four openings in the under structure over which may be positioned four hollow tubes or turrets. The first of these openings has beneath it a pan containing the water vapor and the heater therefor while the remaining three are located over the pan containing the liquid ammonia. It will thus be seen that by rotating the turret, the tubes may be brought into registry with the screened apertures 54 at the feeding and discharging station at which time the light sensitive material to be developed is inserted into a set of four tubes and then the turret is moved either step by step or turned by hand to a position wherein four more of the tubes are loaded and further on until all the tubes of the turret are loaded.

Means is provided for advancing the turret either step by step in an intermittent movement, or continuously or wherein the turret may be disconnected from the automatic driving means such as the motor, and moved by hand. To this end, I provide; as shown in the present instance, an electric motor 62 mounted on one of the arms 8 and this motor drives a train of reducing gearing 64, beveled pinion 66, which in turn meshes with another beveled pinion on a vertical shaft 68. This shaft 68 is arranged to drive one element 70 of a Geneva movement the other element of which constitutes the relatively large wheel 72 mounted on the central shaft 16. This geneva is of the usual type so that, as understood in the art, the main shaft 16 is rotated step by step and between rotation is locked in position.

Means is provided for releasing this Geneva movement feed so that the turret may be rotated at will by hand. To this end the relatively large wheel 72 is slidably mounted on a lower reduced end 74 of the shaft 16 and a suitable shipper lever 76 pivotally mounted as at 78 on a leg 2 is provided for slidably disengaging the large Geneva wheel 72 from its companion member 70. Thus when re-

leased, the turret may be rotated at will. On the other hand, when the Geneva members are connected, the motor will drive the turret step by step in the desired direction. The outer periphery of the turret or table is provided with a downwardly depending flange 80 which is adapted to draggily engage the over-hanging flexible rubber or felt gasket 34 which is carried by the outer upper surface of the containers. This outer rubber gasket is in the nature of a peripheral ring of rubber. In addition I also provide the under surface of the turret or table with another rubber ring or gasket 82 which depends downwardly and engages an inner flanged surface 84 on the container pans and also on the circular rings 20 and 22 forming the under structure. Thus, these two concentric rubber gaskets or rings which engage the depending flange 80 on the turret and also engage the inwardly extending flanges 84 and 86 of the under structure and container pans respectively, provide an adequate sealing means for preventing the escape of the developing gas into the surrounding atmosphere while at the same time permitting the gas to pass upwardly into the towers through the holes in the container pans when the towers come into registration with the openings 32 in the tops of the containers.

I also provide the depending flange 80 of the turret with a plurality of forked portions or slots 88 adapted to be engaged by a pivotally mounted arm 90, the inner end 92 of which is pulled normally downwardly by a spring 94 against an adjustable stop 96 carried by a bracket 98 on the outer end of the under structure.

In addition, I have provided automatic means for breaking the motor circuit after the turret has made one complete revolution from the final discharging position. This mechanism comprises a depending stud 100 carried by the under side of the table or turret adapted to engage a spring plunger 102 mounted in a bracket 104 on an insulation member 106 carried on the outer periphery of the under structure 108. This bracket 104 carries two contacts 110 and 112 adapted to be bridged by the contact member 116 when the head 102 is released under the action of the spring 114 and after the head is passed from under the depressing member 100. This head 102 is placed at a desired point on the stationary under structure so that when the actuating member 100 comes opposite it at a certain period of travel of the rotatable turret, the motor will be broken and the turret stopped. If desired, I may couple up this switch to the electric heating systems in the water pans so that the current in the heating members is also cut out when the turret stops.

It will thus be seen that in accordance with my foregoing disclosure I have provided a

very compact and convenient type of developing apparatus for simultaneously developing a plurality of sheets of light sensitive material by the action of chemically active gas and in a manner so as to preclude the escape of the gas into the atmosphere. By reason of the rotatable turret carrying the plurality of developing towers and the manner in which a battery of these towers may be simultaneously loaded at the feeding station and then the turret rotated to load the remaining towers for further automatic development as the turret is driven by the motor, I am enabled to permit the sequential and practically simultaneous development of any number of sheets of light sensitive material and without the interference of human agency since the machine will come to a stop upon the completion of the developing period. It will also be apparent that by reason of the location of the ammonia pans and particularly the location of the water vapor pan for accelerating the developing action, together with the means for driving the turret carrying towers in the step by step manner, the developing action will go on automatically after having been initiated. In other words, all that is required is that the towers be loaded after which the development will be carried out and the machine brought to a stop. By the utilization of a number of sequentially arranged developing pans, that is, pans containing the liquid ammonia adapted to evolve the gas and also by the position of the number of water containing pans adapted to give off steam or water vapor, I am enabled to accelerate the developing action while at the same time, while providing a plurality of sheets of these water pans, I am enabled to effectively and in a minimum time to secure the complete development of the light sensitive material during its cyclic travel about the sequentially arranged pans.

Having thus described my invention what I claim as new and desire to secure by Letters Patent is:

1. In a developing apparatus, the combination of a shiftable member carrying a plurality of separate developing chambers, means forming a station adapted to supply ammonia developing gas and means for moving said separate chambers successively into connection with said developing gas, and means for supporting light sensitive material in each chamber.

2. In a developing apparatus, the combination of movable means having a plurality of separate developing chambers each having an inlet, means for supporting light sensitive material in each chamber, a source of gaseous developing medium, and means for sequentially connecting each chamber to the source of said medium.

3. In a device of the class described, the combination of a rotatable turret carrying a

plurality of developing towers, means for supporting light sensitive material in each tower, means for connecting the successive towers to a source of gaseous developing medium, said means being controlled by the rotation of the turret.

4. In a developing apparatus, the combination of a rotatable turret having a plurality of developing chambers formed with openings, a pan of developing liquid adapted to evolve developing gas located beneath the turret and means for connecting each of said towers with said pan for causing developing gas to enter said towers, and means for rotating said turret and means for preventing the escape of the gas into the atmosphere while permitting it to pass into each tower.

5. In a device of the class described, the combination of a turret containing a plurality of spaced apart up-standing towers, means for rotating said turret step by step, a plurality of pans beneath said turret, covers for said pans, each cover having a plurality of spaced apart openings therein through which the gas arising from the developing liquid in each pan may pass, means for registering the towers with the openings in the tops of the pans during the rotation of the turret, and means for inserting and withdrawing light sensitive material from said towers.

6. In a device of the class described, the combination of a rotatable turret having a plurality of spaced apart up-standing towers having open bottoms, means for supporting light sensitive material in said towers, a stationary under structure beneath said turret, means for rotating said turret, a feeding station formed by said under structure for inserting and withdrawing light sensitive material from said towers, and a developing station comprising means for holding liquid ammonia beneath said towers in their paths of travel, and means controlled by the rotation of said turret for opening and closing communication between said liquid ammonia and said towers.

7. In a device of the class described, the combination of a rotatable means carrying a plurality of towers adapted to hold light sensitive material, a source of developing ammonia and means controlled by the rotation of said rotatable means for controlling the communication between said developing medium and said towers.

8. In a device of the class described, the combination of a shiftable carrier having a plurality of developing towers, means for supporting light sensitive material therein, a source of developing gas and means controlled by the shifting of said carrier for opening and closing communication between the gas and the towers.

9. In a device of the class described, the combination of a rotatable turret carrying a

plurality of up-standing towers having doors of open construction forming a support for sheets of light sensitive material disposed in said towers, an under structure carrying 5 pans adapted to hold developing liquid and pans adapted to hold water, heating means in said water pans, said pans having tops provided with spaced apart openings through which the water vapor and ammonia gas may 10 rise, means for rotating said turret to register the towers with the openings in said tops of the pans and sealing means adapted to seal the movable connection between the rotatable turret and the under structure and pans 15 for preventing the escape of the ammonia and water vapor.

10. In a device of the class described, the combination of a supporting structure adapted to hold a pan adapted to receive liquid 20 ammonia, a rotatable turret carried by said structure comprising a centrally disposed shaft, a plurality of developing towers on said turret adapted to make and break connection with the pan containing the liquid ammonia, a motor and driving means therefrom to said shaft for rotating said turret step by step.

11. In a device of the class described, the combination of a supporting structure adapted to hold a pan adapted to receive liquid ammonia, a rotatable turret carried by said structure comprising a centrally disposed vertical shaft, a plurality of developing towers on said turret adapted to make and break connection with the pan containing the liquid ammonia, a motor and driving means therefrom to said shaft for rotating said turret step by step, and means for disconnecting the driving means from the turret 40 to permit the turret to be rotated freely by hand.

12. In a device of the class described, the combination of a supporting base holding a pan of liquid ammonia, a top for said base 45 having an opening therein, a turret rotatable over said opening and carrying a plurality of developing towers open at the bottom and adapted on rotation of said turret to register with said opening, means for supporting light sensitive material in said towers, a motor, means for rotating said turret from said opening in step by step movement including a Geneva movement, and means for preventing the escape of the developing gas 55 from said container and from said tower during the rotation of the turret.

13. In a device of the class described, the combination of a supporting base, a vertical shaft thereon, a rotatable turret carried by 60 said shaft, a locking and driving wheel mounted on said shaft, a motor carried by said base, a train of gearing operatively connecting said motor and driving wheel and arranged to drive the wheel in step by step 65 movement and to hold the same in locked po-

sition during movements, a pan of liquid ammonia carried by said base, and means for successively connecting said pan with the respective towers carried by said turret during its rotation, and means for sealing said connection and preventing the escape of the gas 70 therefrom.

14. In a device of the class described, the combination of a supporting base, a source of developing gas carried thereby, a rotatable 75 turret mounted on said base and carrying a plurality of developing towers, means for rotating said turret and connecting said towers successively with said source of gas, and means for stopping said turret upon the completion of a predetermined movement.

15. In a device of the class described, the combination of a supporting base carrying a pan containing liquid ammonia, a rotatable turret having a depending flange provided 85 with a plurality of upstanding developing towers, means for connecting the towers with the source of ammonia, flexible gaskets forming a sealing connection between said rotatable turret and the base for preventing the escape 90 of the ammonia gas.

16. In a device of the class described, the combination of a supporting base, a vertical shaft mounted thereon, a turret mounted on said shaft and having a plurality of upstanding towers, a relatively large Geneva stop wheel mounted on said shaft, a cooperative Geneva wheel mounted on the base, means for driving said second Geneva wheel, arcuately disposed containers mounted on said base at 95 the periphery of the turret and beneath the same and adapted to contain liquid ammonia and water, said containers having tops provided with spaced apart openings disposed so as to register with the towers in the turret in predetermined positions of the turret, and sealing means for preventing the escape of the developing gas from the tank or turret while permitting the same to pass from the tanks 100 into the turret.

17. In the developing apparatus, the combination of a shiftable member carrying a plurality of separate developing chambers, means for supporting light sensitive material in each chamber, means for moving said shiftable member, and means adapted successively to subject the light sensitive material in the separate chambers to the action of heated water vapor and developing gas by reason of the travel of said shiftable member.

18. In a developing apparatus, the combination of a shiftable member carrying a plurality of separate developing chambers, means for supporting light sensitive material in each chamber, means for shifting said member, and means for successively subjecting the light sensitive material in said chambers first to the action of heated water vapor and subsequently to the action of a gaseous developing medium.

19. In a developing apparatus, the combination of a rotatable turret carrying a plurality of separate developing chambers, means for supporting light sensitive material in each chamber, means for shifting said turret, and means forming separate stations for sequentially subjecting successive chambers first to

the action of heated water vapor and next to the action of gaseous developing medium due to the travel of said turret.

10

In witness whereof, I have hereunto subscribed my name.

ADOLPH LANGSNER.
